United States Patent Office

Des. 203,731
Patented Feb. 8, 1966

203,731

CIGARETTE PACKAGE HOLDER

Ted K. Roden, 612 N. Sierra Bonita,
Los Angeles, Calif. 90036

Filed May 19, 1964, Ser. No. 80,059

Term of patent 14 years

(Cl. D85—2)

FIG. 1

FIG. 4.

FIG. 2.

FIG. 3.

FIG. 5.

I claim:

The ornamental design for a cigarette package holder, substantially as shown.
